TOOTHPICK DISPENSER OR SIMILAR ARTICLE

Irving Mayer, 320 W. Mandalay, San Antonio, Tex.

Filed Mar. 18, 1960, Ser. No. 59,780

Term of patent 14 years

(Cl. D52—2)

Fig. 1

Fig. 2

Fig. 3

Fig. 4

Fig. 5

Fig. 6

Fig. 1 is a perspective view of a toothpick dispenser or similar article showing my new design;

Fig. 2 is another perspective view thereof taken diametrically opposite of Fig. 1;

Fig. 3 is a bottom plan view;

Fig. 4 is a top plan view;

Fig. 5 is a front elevational view; and

Fig. 6 is a rear elevational view.

I claim:

The ornamental design for a toothpick dispenser or similar article, as shown.
